UNITED STATES PATENT OFFICE.

GEORG EKLUND, OF WINONA, MINNESOTA.

DESIGN FOR A TOY VEHICLE.

57,894.

Specification for Design.

Patented May 17, 1921.

Application filed November 8, 1920. Serial No. 422,743. Term of patent 7 years.

To all whom it may concern:

Be it known that I, GEORG EKLUND, a citizen of the United States, residing in the city of Winona, county of Winona, and State of Minnesota, have invented a new, original, and ornamental Design for Toy Vehicles, of which the following is a specification, reference being had to the accompanying drawing, forming part thereof.

Figure 1 is a perspective of a toy vehicle showing my new design and Fig. 2 is a side elevation thereof with the seat collapsed.

I claim:

The ornamental design for a toy vehicle, as shown.

GEORG EKLUND.
